United States Patent Office.

WILLIAM DUESLER, OF ST. JOSEPH, MISSOURI.

Letters Patent No. 95,331, dated September 28, 1869.

IMPROVEMENT IN TRIP-HAMMER SAW-SET.

The Schedule referred to in these Letters Patent and making part of the same.

To all whom it may concern:

Be it known that I, WILLIAM DUESLER, of St. Joseph, in the county of Buchanan, and State of Missouri, have invented a new and valuable Improvement in a Combination Trip-Hammer Saw-Set; and I do hereby declare that the following is a full, clear, and exact description of the construction and operation of the same, reference being had to the annexed drawings, making a part of this specification, and to the letters and figures of reference marked thereon.

Figure 1, of the drawings, is a perspective view.

Figures 2 and 3 are details.

My invention relates to means for setting the teeth of saws; and

It consists, mainly, in a novel arrangement of devices intended to serve as efficient means for the purpose named.

To this end I construct a frame, of suitable metal, about nine and one-fourth inches in length, and three and one-fourth inches in height and depth, respectively, of the form and shape represented on the drawings by the letter A. This frame is adapted for attachment to a block or bench, by screws in its flanches, as shown.

On the raised platform, at the front of the frame, I arrange the sliding and adjustable block B, in the manner shown on fig. 1, and I also insert into said raised platform an anvil, at the point C.

The letter D represents a trip-hammer, constructed in the form shown.

Its handle is passed through the rotating shaft E, and extends to the rear thereof, for the purpose hereinafter mentioned.

The letter F represents a spring, attached at one end to the bed-plate of the frame, while its other end rests against the bottom of the handle at the rear of the shaft, as shown.

The letter G represents the trip.

It consists of a shaft, arranged in bearings in the adjustable blocks H, as shown, and having curved arms K, that serve as trips, working upon the rear end of the hammer-handle.

This trip is worked by means of the crank P, attached to the end of the trip-shaft.

The letters K' represent adjustable blocks, arranged to serve as bearings for the trip-shaft, and made adjustable in the side of the frame by means of suitable slots cut in said frame, through which set-screws are passed, uniting the blocks respectively to said frame, in the manner shown.

These slots in the frame are represented by the letter a, and the set-screws by letter c.

Between the heads of these set-screws, respectively, and the sides of the frame, I arrange India-rubber washers, shown at s.

In operating my device, the adjustable block B serves as a guide to regulate the depth of the set in accordance with the length of the saw-tooth, and the blocks K serve as means for regulating the height to which the hammer shall be raised.

What I claim as my invention, and desire to secure by Letters Patent, is—

The machine for setting saws herein described, having frame A, blocks B and K', hammer D, trip G, and spring F, when constructed and arranged substantially as specified.

In testimony that I claim the above, I have hereunto subscribed my name, in the presence of two witnesses.

WILLIAM DUESLER.
